UNITED STATES PATENT OFFICE.

DAVID JOHN THOMAS, OF CARDIFF, AND JOHN VICKERY, OF TONTEG LLANTWIT VARDRE, WALES.

DEVICE FOR BOSHING TINPLATE AND SHEET BAR SECTIONS.

Application filed February 4, 1927, Serial No. 165,879, and in Great Britain February 16, 1926.

This invention relates to a device for boshing articles such as tin plate and sheet bar sections. The existing method of boshing such articles consists in immersing the articles on the end of long tongs such as are used for lifting and carrying metal into a liquid contained in a trough or tank. This method is not only difficult to perform but cumbersome and the result is usually a partial boshing which is unsatisfactory as the article is left in a dirty and porous state. The chief object of this invention is to provide a simple device whereby boshing can be completely and satisfactorily carried out without undue loss of heat in the articles undergoing boshing.

According to the invention the boshing tank consists in the combination of an oscillatory or movable platform for immersing the articles which are carried thereon into the liquid in the tank and means for momentarily immersing said platform in the liquid in said tank and rapidly returning it into a position wherein the boshed articles can be readily removed therefrom. The said platform is immersed into the liquid preferably by means of a lever and returned from the immersing position into a position wherein the boshed articles can be readily removed therefrom by means of counterbalance weights.

In order that the said invention may be clearly understood and readily carried into effect the same will now be described more fully with reference to the accompanying drawings.

Fig. 1 illustrates in perspective a device constructed in accordance with the invention.

Fig. 2 shows an end view of the device of Fig. 1.

A is the boshing tank and D is the platform for immersing the articles carried thereon into the liquid in the tank. The said platform is carried on a spindle E which engages a slot C at one end of the tank and a hole B at the opposite end. The spindle E is shown square throughout the greater part of its length but the portion thereof engaging with the opened top slot C and the hole at B is formed circular to permit rotation thereof. In Fig. 1 a portion of the spindle has been broken away to show the circular cross section thereof in the slot C. By mounting the spindle in this manner the platform can be readily removed when required from the tank by lifting the spindle out of the slot C and drawing it in a direction

which will disengage its end from the hole B. The platform is perforated and made of H shape to give free access of liquid around the articles for thorough boshing and also to give the workman necessary tong room at R 60 for placing and removing them on and from the platform. The outer or free ends of the platform are bent upwards at D¹ and D² to prevent the articles from slipping off when the platform is immersed in the liquid in the tank. F is the foot lever which is of the bell crank type and is attached to the spindle E. W are the counterbalance weights fitted to the lever F, said weights being varied in size or number according to the weight of the articles on the platform D. A bolt or member H of sufficient length passes through the weights W to reach a lever Y which operates to lift a splash plate S on the down or operative stroke of the foot lever F, the lever Y being pivoted on a bolt or spindle K. A similar lever is pivoted at J on the opposite side of the tank A. To perform a boshing operation the foot lever F is depressed whereupon the platform D is turned downwards and becomes immersed in the liquid in the tank thereby subjecting the articles carried by the platform to the boshing operation. On releasing the pressure on the foot lever F the platform is returned to the original position by the counterbalance 70 weights W. When the foot lever is depressed the splash plate is raised as aforesaid to prevent the liquid in the tank from being scattered or thrown outside. A hand door may be fitted for cleaning purposes also suitable inlet 75 and outlet orifices to maintain the correct liquid level in the tank A.

What we claim and desire to secure by Letters Patent of the United States is:—

1. A device for boshing articles such as tin plate and sheet bar sections consisting in the combination of a tank for containing liquid having a platform for carrying the articles to be boshed pivotally mounted on the said tank and means for pivoting said platform whereby the articles are momentarily immersed in the liquid in said tank.

2. A device for boshing articles such as tin plate and sheet bar sections consisting in the combination of a tank for containing liquid having a platform for carrying the articles to be boshed pivotally mounted on the said tank, means for pivoting said platform whereby the articles are momentarily immersed in the liquid in said tank and means for rapidly re-

turning said platform into a position wherein the boshed articles can be readily removed therefrom.

3. A device for boshing articles such as tin plate and sheet bar sections consisting in the combination of a tank for containing liquid having a platform for carrying the articles to be boshed pivotally mounted on the said tank, means for pivoting said platform whereby the articles are momentarily immersed in the liquid in said tank and means for preventing the splashing over of the liquid during the boshing operation.

4. A device for boshing articles such as tin plate and sheet bar sections consisting in the combination of a tank for containing liquid, a platform pivotally mounted in the sides of said tank, a lever for immersing said platform in the liquid in said tank and a counterbalance weight cooperating with said lever for returning said platform from the immersed position into a position wherein the boshed articles can be readily removed therefrom.

5. A device for boshing articles such as tin

plate and sheet bar sections consisting in the combination of a tank for containing liquid, a platform for carrying the articles to be boshed, a spindle on said platform mounted in the sides of said tank, a double armed lever on said spindle, a pedal on one arm of said lever and a counterbalance weight on the other arm of said lever.

6. A device for boshing articles such as tin plate and sheet bar sections consisting in the combination of a tank for containing liquid, a platform for carrying the articles to be boshed, a spindle on said platform mounted in the sides of said tank, a double armed lever on said spindle, a pedal on one arm of said lever, a counterbalance weight on the other arm of said lever, a slidably mounted shield plate having levers at its ends pivoted to said tank and a member extending from said counterbalance weight and engaging with one of said levers for raising said shield plate into its splash preventing position.
